UNITED STATES PATENT OFFICE.

VINNIE F. CREEGAN, OF LOS ANGELES, CALIFORNIA.

SOAP HOLDER FOR BRUSHES.

Application filed March 6, 1926. Serial No. 92,876.

My invention relates to and has for its purpose the provision of an extremely simple and inexpensive device capable of being readily applied to various forms of brushes, such as bath and dish washing brushes, either fountain or plain, and which is operable to securely retain a cake of soap in such position on the brush as to permit by manipulation of the brush the application of soap to the surface of the object being cleaned, and yet allowing the normal use of the brush in scrubbing the surface following the application of soap thereto.

It is also a purpose of my invention to provide a soap holder for brushes which is readily detachable from the brush in the event it is desired to not use the holder, and a holder which is adjustable to receive and firmly hold soap cakes of various sizes.

I will describe only one form of brush and one form of soap holder each embodying my invention, and will then point out the novel features thereof in claims.

In the drawings

Figure 1 is a view showing in plan one form of brush and one form of soap holder, each embodying my invention;

Figure 2 is a section taken on the line 2—2 of Figure 1;

Figure 3 is a view similar to Figure 2, showing the position of the soap holder just prior to its movement to locked position;

Figures 4 and 5 are sectional views taken on the lines 4—4 and 5—5, respectively, of Figure 2, with Figure 5 disclosing the expanding tool embodying my invention in applied position to the soap holder.

Similar reference characters refer to similar parts in each of the several views of the drawings.

Referring specifically to the drawings, my invention in its present embodiment comprises a brush which in the present instance is shown as a fountain bath brush, and it comprises a handle 15 including a ferrule 16 provided with an opening 17, and a brush head including a twisted wire frame shaped to provide spaced parallel portions 18 and bristles 19 secured to the frame so as to form a substantially U-shaped brush head. The handle 15 is bored to receive a pipe 20. This pipe, as shown in Figure 2, extends through the ferrule 16, with a perforated portion 20^a extending between the parallel

portions 18 of the frame so as to be disposed between the parallel portions of the bristles 19.

The soap holder in the present instance comprises a single sheet of suitable resilient metal, such as steel or brass, shaped to provide a body portion 21, from one end of which extends a transversely curved shank 22 offset with respect to the body portion and having on its free end a latching finger 23. The body portion is stamped to provide two reversely disposed grooves 24 and 25, the confronting ends of which are separated by a transverse slot 26. These two grooves co-operate to provide a channel for the reception of the pipe extension 20^a in a manner clearly illustrated in Figure 3.

On the longitudinal edges of the body portion 21 upstanding and converging jaws 27 are formed, the free longitudinal edges of which are inturned and serrated, as indicated at 28, so that when the jaws are placed under tension the serrated edges will operate to firmly clamp a cake of soap. These jaws are formed with openings 29 in which are received offset lugs 30 formed in the ends of a pair of arms 31 connected by a leaf spring 32 and constituting an expanding tool by which the jaws can be manually moved to expanded position as shown in Figure 5.

In practice, the soap holder is slipped over the free end of the pipe extension 20^a so that the latter is received in the grooves 24 and 25, when the soap holder may be moved along the pipe extension in the direction of the ferrule until the latching finger 23 is opposite the opening 17 of the ferrule, as clearly shown in Figure 3. The channel formed in the grooves 24 and 25 is such that the soap holder normally occupies the inclined position shown in Figure 3, so that in order to move the latching finger into the opening 17 it is necessary to press the shank 22 downwardly as indicated by the arrow in Figure 3 against the tendency of the soap holder to occupy the inclined position. In this operation the grooved portions of the soap holder are placed under tension, and it will thus be seen that by moving the soap holder inwardly the latching finger will be moved to engage within the ferrule as shown in Figure 2 and maintained in such position by the tendency of the soap holder to

return to its inclined position. Thus the soap holder now occupies the position shown in Figure 2, in which it is firmly but releasably secured against movement on the brush. By applying the expanding tool to the soap holder as shown in Figure 5, the jaws 27 may be expanded to receive a cake of soap in edgewise position so that upon release of the jaws they will return to normal position and thus embed their serrated edges in the cake of soap, as shown in Figure 4, to firmly clamp the soap to the holder. The soap is thus positioned in projecting relation to one side of the brush head so that by manipulation of the brush the soap can be applied to the body, and following such application the reverse side of the brush head can be used in the usual manner.

If it is desired to remove the soap holder from the brush it is only necessary to move the holder forwardly on the brush until the latching finger disengages the ferrule, when the finger will spring to the position shown in Figure 3, so that the holder can be moved forwardly along the pipe extension and finally removed from the free end of the latter.

Although I have herein shown and described only one form of brush and one form of soap holder each embodying my invention, it is to be understood that various changes and modifications may be made therein without departing from the spirit of the invention, and the scope and spirit of the appended claims.

I claim:

1. In combination, a brush having a handle and an extension projecting from the handle and disposed adjacent the bristles of the brush, and a soap holder comprising means for holding a cake of soap, means on the soap holding means by which the latter is attached to the extension, and coacting means on the soap holding means and handle by which said holding means is secured in fixed position on the extension.

2. In combination, a brush having a handle and an extension projecting from the handle and disposed adjacent the bristles of the brush, and a soap holder comprising means for holding a cake of soap, means on the soap holding means by which the latter is attached to the extension, resilient means on said holding means, and coacting means on the resilient means and handle adapted to secure said holding means in fixed position on the extension.

3. In combination, a brush having a handle, a ferrule on the handle and provided with an opening, an extension projecting

from the handle and disposed adjacent the bristles of the brush, and a soap holder comprising means for clamping a cake of soap, means on the clamping means by which the latter is attached to the extension, and means on the clamping means coacting with the ferrule opening to secure the soap holder in fixed position on the extension. 65

4. In combination, a brush having a handle, a ferrule on the handle and provided with an opening, an extension projecting from the handle and disposed adjacent the bristles of the brush, and a soap holder comprising means for clamping a cake of soap, means on the clamping means by which the latter is attached to the extension, and resilient means on the clamping means having latching means coacting with said ferrule opening when the resilient means is flexed, to secure the clamping means in fixed position on the extension. 70

5. In combination, a brush having a handle, a ferrule on the handle and provided with an opening, an extension projecting from the handle and disposed adjacent the bristles of the brush, and a soap holder comprising means for clamping a cake of soap, means on the clamping means by which the latter is attached to the extension, and resilient means on the clamping means having a latching finger capable of latching engagement with said ferrule opening upon flexing of the resilient means so as to utilize the tension set up by such flexure to secure the clamping means in fixed position on the extension. 85

6. A soap holder comprising a body portion having jaws between which a cake of soap is adapted to be gripped, a sleeve on the body in which an extension projecting from a brush handle, is adapted to be received so as to attach the body to the extension, a shank extending from the body, and latching means on the shank adapted to coact with the handle of the brush in a manner to secure the holder in fixed position on the extension. 100

7. A soap holder comprising a body portion of U form constituting resiliently connected jaws between which a cake of soap is adapted to be gripped, said body portion being slotted and provided with a pair of reversely disposed grooves arranged in end to end relation at opposite sides of the slot and having their confronting ends terminating at said slot, the grooves co-operating to define a sleeve, a shank extending from one end of the body portion, and a latching finger on the free end of the shank. 110
